UNITED STATES PATENT OFFICE.

GEORGE W. KERN, OF OIL CITY, PENNSYLVANIA.

IMPELLING DEVICE FOR FLUID-CIRCULATING SYSTEMS.

1,082,594.

Specification of Letters Patent. Patented Dec. 30, 1913.

Application filed February 12, 1913. Serial No. 747,980.

To all whom it may concern:

Be it known that I, GEORGE W. KERN, a citizen of the United States, residing at Oil City, in the county of Venango and State of Pennsylvania, have invented certain new and useful Improvements in Impelling Devices for Fluid-Circulating Systems, of which the following is a specification.

The object, construction and application 10 of my improved fluid-impeller for circulating systems, are herein set forth with sufficient clearness to enable those skilled in the art to which it most nearly appertains, to make and use the same.

15 My device is applicable to various uses, but in order to clearly illustrate one use to which it is well adapted, I have shown in the drawings, which form a part hereof, how it may be applied to automobile service, for 20 the purpose of accelerating the circulation of the cooling-water between the water-jackets of the motive-cylinders and the radiator in which the water is cooled after it has passed through said jackets.

25 In said drawings: Figure 1 is a side elevation partly in longitudinal section of my improved impelling-device; Fig. 2 is a side elevation of a portion of an automobile-motor and a radiator, showing my impelling-device interposed in one of the circulating-pipes.

In many of the automobiles, the circulation of the cooling-water through the cylinder-jackets and the radiator is dependent 35 upon the difference in specific gravity of water at different temperatures, but this method has been found inadequate to effect the proper cooling of the cylinders. In some cases, however, mechanical appliances are 40 employed for the purpose of forcing or accelerating the circulation, but, so far as applicant is aware, all of such appliances are, to a certain extent, cumbersome, and are so constructed that, in case of such an accident to their driving-mechanism as would render them inoperative, their presence within the system greatly impedes the circulation of the cooling-fluid, or wholly prevents the same.

45 The object of this invention, therefore, is, to provide an impelling-device which may be readily introduced in a circulating-system for the cooling-fluid of various forms of motors, to accelerate the movement or flow 50 of said cooling-fluid, and which, in case its driving-mechanism should become inopera-

tive for any reason, will not materially obstruct the natural circulation of said fluid.

The construction shown in the drawings is substantially as follows:

Referring to Fig. 1, the wall of any suitable form of pipe or conduit 1 has an opening 2 formed in the wall thereof for the insertion of a revoluble fluid-impelling device which is composed of a central plate or hub 3 provided with several radiating vanes 4, symmetrically placed, and twisted so as to form part of the same helical surface, or approximately so shaped. It will thus be seen that said fluid-impeller is a propeller-shaped device closely resembling the familiar form of screw-propeller. Said impelling device is rigidly secured to a suitable shaft 5, which extends through a bearing 6 and is provided upon its outer end 70 with any suitable means which is operable to revolve said shaft and impeller, a pulley 7 being shown for this purpose, though other means, as a small electric motor could be used. As shown in the drawings, the bearing 6 has, formed integrally therewith, a saddle 8, the inner, concave face of which, conforms to the periphery of the conduit 1 to which it is attached by means of clamps 9. The outer end of bearing 6 is provided with 80 a suitable stuffing-box 10 to prevent leakage of fluid around the shaft. As is clearly shown in said Fig. 1, shaft 5 passes obliquely through the wall of said conduit, 1 and because of this position, the plane of rotation of the impeller is positioned obliquely to the axis of said conduit, hence it is not necessary to provide an irregularly-shaped conduit in order to permit the insertion of my impelling device therein.

95 One method of applying my impelling device is shown in Fig. 2 which method is substantially as follows:—One end of the conduit 1 is secured to the nipple 11 or water-inlet to the water-jacket of the motor 100 cylinders, by means of a flexible connection 12, and the other end of said conduit is connected to the water-outlet 13 of the radiator 14 by means of a flexible connection 15. A pulley 16 is secured to the shaft of the fan 105 17 and a belt 18 transmits motion therefrom to pulley 7, shaft 5 and the thereto-attached impelling device, and said motion of the impeller causes an acceleration in the flow of fluid through conduit 1 and consequently, 110 through the whole circulating system in which it is located.

If necessary or desirable, any suitable packing, as 19, may be placed between the contacting surfaces of the saddle 8 and conduit 1, to prevent leakage of the cooling-fluid.

5 I claim—

1. The combination with a fluid-conduit, of a revoluble, fluid-impelling device, located within said conduit and consisting of 10 a propeller-shaped device, with its plane of rotation arranged obliquely to the axis of said conduit, a shaft for said impelling-device, extending through the wall of said conduit, and means upon the outer end of 15 said shaft, operable to revolve said impelling-device.

2. The combination with a fluid-conduit, of a revoluble, fluid-impelling device, positioned within said conduit, with its plane 20 of rotation arranged obliquely to the axis of said conduit, a shaft to which said impelling-device is affixed, extending obliquely through the wall of said conduit, a suitable bearing for said shaft, and means upon the 25 outer end of said shaft operable to revolve said impelling-device.

3. The combination with a circulation pipe for the cooling-fluid of an internal-combustion motor, of a revoluble impelling 30 means positioned within said pipe consisting of a propeller-shaped device having its

plane of rotation disposed obliquely to the axis of said pipe, a shaft to which said impelling device is secured, said shaft extending obliquely through the wall of said pipe, 35 a bearing for said shaft, and means operable to revolve said shaft and the thereto-attached impelling device.

4. The combination with a circulation-pipe for the cooling-fluid for the motive-cylinder of an internal-combustion motor, of a separable section of pipe adapted to be interposed in said circulation-pipe, a revoluble fluid-impelling means positioned within said separable section consisting of a propeller-shaped device having its plane of rotation disposed obliquely to the axis of said section, a shaft to which said impelling-device is secured, said shaft extending obliquely through the wall of said separable 50 section, a suitable bearing for said shaft, means operable to rotate said shaft and the thereto-attached impeller, and flexible means connecting said separable section in said circulation pipe.

55 In testimony whereof I affix my signature in presence of two witnesses.

GEORGE W. KERN.
